SWIVEL DEVICE

Philip Magid, Brooklyn, N. Y.

Application April 27, 1939, Serial No. 270,376

7 Claims. (Cl. 59—95)

This invention relates to swivel devices and more particularly to a detachable swivel device for gun slings and gun straps.

One of the objects of my invention is to provide a pair or a plurality of removable swivel devices for readily adjusting, attaching and detaching gun slings and gun straps.

Another object of my invention is to provide a swivel device of novel construction which can be readily assembled and used with great facility.

Another object of my invention is to provide a swivel device having a loop in combination with a bushing of novel construction, in which the loop may be readily and easily detached from said bushing but cannot be accidentally dislodged therefrom.

Another object of my invention is to provide a removable swivel device for gun slings and gun straps which will not interfere with the use 20 of the gun and will render the same more efficient and suitable for accurate shooting.

Other objects of my invention will be set forth in the following description and drawing, which illustrate a preferred embodiment thereof, it being understood that the above statement of the objects of my invention is intended generally to explain the same without limiting it in any manner.

Fig. 1 is a side view of a gun having a set of 30 my swivel devices attached thereto, the gun being shown partly broken away.

Fig. 2 is an enlarged front view of the swivel device, partially in section.

Fig. 3 is a side view thereof.

Fig. 4 is a view showing the loop member partially inserted into the bushing, said bushing member being shown in section, and the loop member being shown partly broken away.

Fig. 5 is a front view of the device in un-assembled condition, the loop member being shown broken away for the convenience of illustration.

Referring to the drawing, particularly to Fig. 1 thereof, R generally designates a gun or rifle 45 of the usual type having a forestock 1 and a butt B.

My swivel device broadly includes a socket element M and a swivel element N. More specifically, socket element M comprises a threaded bolt 2, having a hollow, cylindrical, internally threaded head 4. Said head 4 is provided with diametrically opposed slots 8, said slots being adapted to accommodate a screw driver or any other suitable tool. A nut 3 is employed to secure each socket element M within the vertical

grooves of forestock 1, as shown in Fig. 1. A single socket element M or any desired number thereof is permanently mounted within the vertical grooves provided in forestock 1 so that the bottom of each head 4 is flush with the under surface of forestock 1 and that part of the forestock is smooth and has no projections. It is obvious that by employing a plurality of socket elements M, it is possible to quickly alter the length and degree of looseness of straps S and 10 make any desired adjustments thereof, without unbuckling said strap.

As shown in Fig. 2, swivel element N comprises three parts, namely, bushing member 11, cap screw 7 and non-continuous loop 16.

Bushing member 11 is formed with a vertical bore 12 for receiving the shank of cap screw 7. It will be noted that the lower part of bore 12 is threaded at 13, as shown in Fig. 4. It will also be noted that bushing 11 is generally of a 20 truncated conical shape, having an upper bevelled side edge. Bushing 11 is also formed with a horizontal bore 14 of slightly larger diameter than the diameter of the transverse cross section of loop 16. An inclined bore 15 of substantially 25 larger diameter than bore 14 is formed at the left side of bushing 11. Said bore 15 is formed so as to permit one of the free ends 16a of loop 16 to be inserted into the bushing.

In order to assemble loop 16 and bushing 11, 30 loop 16 is tilted at an angle relative to bushing 11 and free end 16a of said loop is inserted through bore 15 until said free end almost abuts the opposite wall of said bushing, as shown in Fig. 4. Loop 16 is then turned relative to bushing 11 until the free ends of said loop lie parallel to bore 14. Bushing 11 is then moved so that the right free end of loop 16 is inserted into bore 14. The shank of cap screw 7 is then inserted into vertical bore 12, thus completing the assembly of the swivel element.

One of the advantages of being able to readily disassemble loop 16 from bushing 11 is that strap S may be readily inserted through loop 16 without unbuckling said strap. This is shown in Fig. 45 45, strap S being shown in dotted lines.

As will be clearly observed from Fig. 2, cap screw 7 is formed with the head 9, said head having a diametral slot 10 formed therein. Said slot 10 is adapted to receive a screw driver, tool, 50 or coin for the purpose of making adjustments. It will be noted that the portion of the shank of cap screw 7 directly adjacent head 9 is not threaded and this unthreaded area is designated by the reference numeral 8. The purpose of this 55

is to permit bushing 11 and loop 16 to be freely rotatable before cap screw 7 is tightened. This allows the loop and bushing to be fixed in any desired position.

- 5 While I have shown in the various figures of the drawing, the swivel element N assembled with the bushing member 11 in the position in which its bottom face is adjacent cap screw 7, I do not wish to be limited to this arrangement.
- 10 Bushing member 11 may be in the reverse position than that illustrated in the drawing. That is, it may be assembled with its upper bevelled edge adjacent cap screw 7. In this position, it will function just as effectively and efficiently 15 as in the position illustrated in the drawing.

Referring again to Fig. 1, a threaded, straight type, coarse wood screw is set in butt B so that the bottom of the head of said screw is flush with the under surface of butt B. The construction of the head of screw 17 is identical with the construction of the head of bolt 2 previously described. Swivel device N having loop 18 mounted thereon can then be attached to the head of screw 17 so that the entire adjusting device is ready for use.

20 As will be discerned from Fig. 3, loop 16 is of generally curved or arcuate form. Loop 18, however, is of the usual flat form. The purpose of using a curved loop 16 for the front swivel 25 only is for accommodating the hand so that the swivel device may be used with the greatest comfort and ease when the gun is handled or fired.

The principal object of my particular bushing construction is to allow easy assembling of 30 the loop onto said bushing. Because of this feature, the loops may be manufactured in mass production and shaped before insertion into the bushing; whereas in the usual type of gun swivel bushings, each loop must be shaped in the bushing and this performance entails greater expense and labor.

I have shown a preferred embodiment of my invention but numerous alterations and omissions may be made without departing from its 45 spirit. Likewise, my improved swivel device and bushing member per se may be readily employed

and adapted for use other than with guns or fire arms and I therefore do not desire to be limited to use thereof only in connection with guns, etc.

I claim:

1. A bushing having a cylindrical body portion with a vertical bore formed therein, said vertical bore being adapted to receive the shanks of a screw or the like, said body having a pair of diametrically opposed horizontal bores formed therein, one of said horizontal bores having at least one of its faces inclined to a horizontal plane, said horizontal bores being adapted to receive the free end of a loop or the like. 5

10 2. A bushing as claimed in claim 1 in which the body member has a truncated conical shape. 15

3. A swivel device of the character described comprising a socket element and a swivel element releasably connected to each other, said swivel element comprising a bushing member, a cap screw and a loop, said bushing having a vertical and horizontal bore formed therein, said bores intersecting each other, one of said horizontal bores having at least one of its faces inclined to a horizontal plane. 20

4. A swivel device as claimed in claim 3 in which the bushing member is of truncated conical shape. 25

5. A swivel device as claimed in claim 3 in which a portion of the shank of the cap screw is not threaded. 30

6. A swivel device as claimed in claim 3 in which a portion of the vertical bore of the bushing is threaded.

7. A swivel device comprising a socket having an opening in its inner end for the reception 35 of a swivel element, said swivel element comprising a bushing, a cap screw and a loop, said bushing having a vertical bore adapted to receive the shank of the cap screw, said bushing having a pair of diametrically opposed horizontal 40 bores formed therein, said horizontal bores being adapted to receive the free ends of the loop, one of said horizontal bores having at least one of its faces inclined to a horizontal plane. 45
